OF HOPEDALE, MASSACHUSETTS, A CORPORATION OF MAINE.

FEELER MECHANISM FOR LOOMS.

1,387,201.

Specification of Letters Patent. Patented Aug. 9, 1921.

Application filed October 7, 1919. Serial No. 328,979.

To all whom it may concern:

Be it known that I, ISAAC SNOW, a citizen of the United States, and a resident of Lawrence, county of Essex, and State of Massachusetts, have invented an Improvement in Feeler Mechanism for Looms, of which the following description, in connection with the accompanying drawings, is a specification, like characters on the drawings 10 representing like parts.

The invention to be hereinafter described relates to feeler mechanisms for looms, and more particularly to feeler mechanisms of the so-called "side swipe" type wherein re- 15 plishment of filling or other change in the running condition of the loom is effected prior to complete exhaustion of the filling in the running shuttle.

The object of the present invention is to 20 provide a feeler mechanism of the side swipe type which shall be simple in construction and effective and sensitive in operation. To these ends, one of the features of the present invention consists of a feeler which is held 25 in its backwardly extending feeling position by spring means, and which spring means is tensioned by forward movement of the feeler, thereby tending to move the feeler longitudinally of the shuttle as it moves 30 forwardly on a detecting beat.

Other features and novel combinations of parts will be hereinafter described in addition to the above and in connection with the accompanying drawings which form one 35 good practical form of the invention, and the novel features thereof will then be described in the claims.

In the drawing:

Figure 1 is a perspective view of the detecting side of the loom showing the feeler mechanism which constitutes the present invention and its associated parts;

Fig. 2 is an enlarged plan view showing the action of the feeler mechanism when the filling is substantially exhausted;

Fig. 3 is a view similar to that of Fig. 2 showing the feeler in its normal or rearward position, and the relation of the associated parts.

In the drawing the filling replenishing mechanism and other portions of the loom construction which are not intimately associated with the present invention are not shown, because these parts may be of usual 50 construction and are well known in the art.

The loom frame 1 has secured thereto the brackets 2, one at each side of the loom, in which is mounted the usual transverse or rock shaft 3 from which rises the finger 4 having pivoted thereto at 5 the latch 6, the rear end portion 7 of which is adapted at times to be engaged by an operating member 8. The operating member 8 may be any suitable moving part of the loom timed properly to effect replenishment when the 65 shuttle is at the filling replenishing side of the loom, and in the present instance, is indicated as a part connected to the cam follower.

The lay has mounted thereon the usual 70 shuttle-box 9, the front wall of which is slotted at 10 to register with the slot 11 of the shuttle 12 when the latter is in the detecting box. The shuttle 12 carries the usual filling carrier or bobbin 13 on which the 75 filling is wound. The parts so far described are or may be of usual construction common in feeler looms.

The shipper stand 14 has extending therefrom the bracket 15 slotted at 16, and to the 80 slotted portion of the arm 15 is adjustably secured the bracket 17 by means of the bolt 18 or other form of securing means. Adjustably secured to the bracket 17 is the feeler stand 18 which may be connected to 85 the bracket by the screws 19 passing through a slot in the feeler stand as indicated in Fig. 1 to permit adjustment of the feeler stand toward and from the rear of the loom.

Mounted for movement toward and from 90 the rear of the loom on the feeler stand 18 is the slide or carrier 20 which may be guided for its reciprocating movement by suitable means, such, for instance, as the slotted flange 21 rising from the rear portion of the feeler stand, and a guide 22 extending upwardly from the feeler stand and engaging a slot 23 longitudinally of the slide or carrier 20, the construction being such that as the carrier or slide 20 is moved toward and from the front 95 100 of the loom, it shall be guided for such movement.

Pivottally mounted upon the carrier at 24 is the feeler 25, the rear end portion of which is provided with teeth 26 for engagement with the surface within the shuttle on a detecting beat. The feeler 25 is thus mounted upon the carrier for swinging movement about its pivotal connection therewith, and suitable means is provided for 105 110

limiting the swinging movement of the feeler. In the present instance, the feeler has secured thereto at its forward end portion a stop member 25, the downturned ends 5 26 of which are adapted to engage the side of the carrier 20 and thereby limit the swinging movement of the feeler.

It is desirable that the feeler and its connected slide shall be held normally in rearward position to permit the feeler to enter the shuttle and detect the condition of filling therein, and when the feeler is moved forwardly on a detecting beat, it should be subjected to a force tending to move it or swing 10 it about its pivotal connection with the carrier in a direction longitudinally of the shuttle. To this end the feeler is connected with a yielding element which normally tends to hold the feeler yieldingly in its 15 rearward position, and is placed under stress by the forward movement of the feeler on a detecting beat, tending to give the feeler a movement longitudinally of the shuttle.

In the present instance, the feeler stand 25 has extending laterally therefrom the arm 27 having an upstanding flange 28 provided with a series of openings 29, and two springs 30 and 31 are connected to the feeler at opposite sides of its pivotal connection 24 with 30 the feeler carrier, and converge laterally from the feeler carrier and are connected at their outer ends 32 with the flange 28 of the arm 27. The direction of pull of the two springs 30 and 31 is such that when the lay 35 is in its rearward position, they act through the feeler to move the feeler and carrier 20 rearwardly to present the feeler in its rearward feeling position as indicated in Fig. 1. When, however, the feeler is moved forwardly on a detecting beat, the tension of 40 the spring 31 is increased over that of the spring 30 to an amount sufficient to impart a tendency to the feeler 25 to movement in a direction longitudinally of the shuttle. In 45 order that the relative action of the springs 30 and 31 may be properly adjusted to secure the functional operation stated, the feeler 25 is provided with the holes 33 and 34 by which the ends of the springs 30 and 31 50 which are connected to the feeler at opposite sides of its pivotal connection 24 with the feeler carrier may be adjusted.

In order to limit the rearward movement of the feeler carrier and feeler, the feeler 55 may be provided with a stop or shoulder 35, which, when the feeler is in its rearward position, engages the flange 21.

When a working supply of filling is present in the shuttle on a detecting beat, the 60 toothed rear end 26 of the feeler engages and sinks into the filling, and as the lay continues forwardly, the feeler member and carrier 20 are pushed forwardly, thus increasing the tension of the spring 31 and decreasing the tension of the spring 30 and

thereby imparting to the feeler a tendency to movement longitudinally of the shuttle, which, however, is resisted by the toothed end 26 of the feeler engaging the filling. When, however, the filling has become substantially exhausted and there is no longer sufficient filling to resist the tendency of the spring 31 to move the feeler in a direction longitudinally of the shuttle on a detecting beat, the toothed end 26 of the feeler will 70 slip along the surface within the shuttle as the feeler and carrier are pushed forwardly on a detecting beat.

The present invention contemplates that this movement of the feeler in a direction 80 longitudinally of the shuttle which indicates substantial exhaustion of filling may be utilized to act through a train of mechanism to effect replenishment of filling. In the present instance, a lever 36 is pivotally 85 mounted at a fixed point preferably on the feeler stand 18 at 37, and its rear end portion 38 bears against the feeler 25 under the impulse of a spring 39, one end of which is connected to the lever 36 at 40, and the 90 other end to a fixed point at 41. The front end portion of the lever 36, in the present instance, is connected at 42 with a transmitter 43 which is connected at its other end to a lever 44 pivoted at 45 to a stand 46 rising from the loom frame. The lever 44 has a finger portion 47 underlying the latch 6, the construction being such that when the feeler is moved in a direction longitudinally of the shuttle due to substantial exhaustion 95 of filling on a detecting beat, the end 7 of the latch 6 will be placed in operative relation with the operating member 8, and filling replenishment will be effected.

What is claimed is:—

1. In a feeler mechanism for looms, the combination of a feeler stand, a feeler carrier mounted on the stand for movement toward and from the front of the loom, a feeler pivotally connected to the feeler carrier, two springs one connected to the feeler rearwardly of its pivotal connection with the feeler carrier, and the other connected to the feeler forwardly of its pivotal connection with the carrier, and normally acting to hold the feeler and feeler carrier rearwardly in feeling position, and having their relative tensions changed to cause movement of the feeler in a direction longitudinally of the shuttle when the filling is substantially exhausted on a detecting beat, and means actuated by movement of the feeler longitudinally of the shuttle to effect replenishment of filling.

2. In a feeler mechanism for looms, the combination of a feeler carrier mounted for movement toward and from the front of the loom, a feeler pivotally connected between its ends to the feeler carrier, a spring connected to the feeler at one side of its pivotal con- 130

nection with the feeler carrier, a spring connected to the feeler at the other side of its pivotal connection with the feeler carrier, said springs normally acting by their relative tension to hold the feeler and carrier in rearward feeling position and tending to move the feeler in a direction longitudinally of the shuttle when the feeler carrier is moved frontwardly by the surface within the 10 shuttle on a detecting beat.

3. In a feeler mechanism for looms, the combination of a feeler carrier mounted independently of the lay, a feeler connected to the carrier for movement in a direction longitudinally of the shuttle, and held from such movement longitudinally of the shuttle by engagement with the filling on a detecting beat until substantial exhaustion thereof, two springs which act upon the feeler in a 15 direction inclined to the longitudinal axis of the feeler to normally maintain the feeler and carrier in rearward feeling position, and tensioned by the frontward movement of the feeler to place such feeler under a tendency 20 to move longitudinally of the shuttle as the feeler moves frontwardly on a detecting beat.

4. In a feeler mechanism for looms, the combination with a feeler carrier mounted independently of the lay for movement toward and from the front of the loom, a feeler pivotally connected thereto for movement in a direction longitudinally of the shuttle, and held from such movement longitudinally of the shuttle by engagement with 30 the filling on a detecting beat until substantial exhaustion thereof, spring means acting laterally upon the feeler to maintain the feeler and carrier in rearward feeling position, and tensioned by the frontward movement of the feeler under the frontward push 35 of a surface within the shuttle on a detecting beat to place such feeler under a tendency to move longitudinally of the shuttle as the feeler moves frontwardly, and stops for 40 limiting the movement of the feeler longitudinally of the shuttle.

5. In a feeler mechanism for looms the combination of a feeler carrier, a feeler connected thereto for movement longitudinally 50 of the shuttle and held from such movement by engagement with the filling until substantial exhaustion thereof on a detecting beat, two springs, one connected to the feeler

and acting diagonally in a rearward direction thereon, and the other connected to the feeler and acting diagonally in a frontward direction thereon to normally maintain the feeler in its rearward feeling position and having their relative tensions changed by frontward movement of the feeler to effect 55 movement thereof in a direction longitudinally of the shuttle when the filling is substantially exhausted on a detecting beat.

6. In a feeler mechanism for looms the combination of a feeler mounted independently of the lay for movement toward and from the front of the loom and longitudinally of the shuttle, spring means tensioned by movement of the feeler toward the front of the loom to urge the feeler longitudinally 60 of the shuttle, means for effecting replenishment of filling upon movement of the feeler longitudinally of the shuttle, and spring means tensioned by movement of the feeler toward the rear of the loom to move the 65 feeler laterally to its normal feeling position.

7. In a feeler mechanism for looms the combination of a feeler supported independently of the lay for movement toward and from the front of the loom, and mounted for 70 movement in a direction longitudinally of the shuttle but held from such movement by engagement with the filling until substantial exhaustion thereof, and two springs connected to the feeler at different points in its 75 length, the tension of one being increased and the other decreased by frontward movement of the feeler.

8. In a feeler mechanism for looms, the combination of a feeler carrier mounted on 80 a fixed part of the loom for movement toward and from the front of the loom, a feeler pivotally mounted on the carrier for movement longitudinally of the shuttle, two springs connected to the feeler and acting at 85 an angle to each other to effect a normally resultant force to hold the feeler carrier in its rearward position and the feeler in its 90 feeling position and tensioned by the frontward movement of the feeler to exert a resultant force upon the feeler tending to move it in a direction longitudinally of the shuttle.

In testimony whereof, I have signed my name to this specification.

ISAAC SNOW.
